(57) **CLAIM**

The ornamental design for a packaging tray, as shown and described.

DESCRIPTION

FIG. 1 is a top, front perspective view of a packaging tray;
 FIG. 2 is a top, rear perspective view of the packaging tray;
 FIG. 3 is a top, plan view of the packaging tray;
 FIG. 4 is an end view of the packaging tray;
 FIG. 5 is an opposing end view of the packaging tray;
 FIG. 6 is a front view of the packaging tray;
 FIG. 7 is a rear view of the packaging tray;
 FIG. 8 is a bottom, front perspective view of the packaging tray;
 FIG. 9 is a bottom, rear perspective view of the packaging tray; and,
 FIG. 10 is a bottom, plan view of the packaging tray.
